UNITED STATES PATENT OFFICE.

CHARLES CASSENEUVE, OF WEST HOBOKEN, NEW JERSEY, ASSIGNOR TO THE LOWELL MANUFACTURING COMPANY, OF MASSACHUSETTS.

DESIGN FOR CARPET.

SPECIFICATION forming part of Design No. 24,648, dated August 27, 1895.

Application filed July 12, 1895. Serial No. 555,776. Term of patent 3½ years.

To all whom it may concern:

Be it known that I, CHARLES CASSENEUVE, a citizen of France, and a resident of West Hoboken, county of Hudson, and State of New Jersey, have invented a new and original Design for Carpets and Borders, of which the following is a specification.

This invention comprises two parts—namely, the design A for carpet and the design B for border; and I do hereby declare that the drawing accompanying this specification conveys to any one a clear understanding of the same, and is sufficient to enable such person to use my invention.

15 The design A is characterized by separate figures made up of clusters of intertwined leaf and floral forms which constitute its leading feature.

The design B is characterized by clusters

similar to those in the design A and outwardly branching leaf and floral forms, which constitute its leading feature.

What I claim, and desire to secure by Letters Patent, is—

1. In a design for carpet, the body A, substantially as shown.

2. In a design for carpet, the border B, substantially as shown.

3. In a design for carpet, the body A and the border B, substantially as shown.

In testimony whereof I have signed my name to this specification in the presence of two subscribing witnesses.

CHARLES CASSENEUVE.
